ATTORNEY

UNITED STATES PATENT OFFICE

WILLIAM CARMAN, OF ELLENVILLE, NEW YORK

POCKETKNIFE

Application filed October 6, 1927. Serial No. 224,447.

This invention relates to pocket knives, and has for an object to provide an improved construction wherein a proper spring action is provided for the respective blades of the 5 knife without presenting the usual wearing surface on the spring back.

Another object of the invention is to provide an improved knife, wherein the back is made separate from the spring means.

10 A still further object of the invention is to provide a knife wherein the various blades of the knife co-act with spring means and with a pin moving in the arc of a circle, whereby the blades are held open or closed.

15 In the accompanying drawing—

Figure 1 is a longitudinal sectional view through a pocket knife disclosing an embodiment of the invention.

Figure 2 is a view similar to Figure 1 but 20 showing the blades in different positions.

Figure 3 is a sectional view through Figure 1 on line 3—3, the same being on an enlarged scale.

Figure 4 is a sectional view through Figure 25 1 on line 4—4, the same being on an enlarged scale.

Figure 5 is an enlarged detail fragmentary perspective view of the shank end of one of the blades shown in Figure 1.

30 Referring to the accompanying drawing by numerals, 1 and 2 indicate the blades, and 3 indicates what may be termed the body. This body may be held together by any desired number of rivets. Three principal rivets have been shown, namely, rivets, 4, 5 35 and 6. Rivets 4 and 6 act as journal pins for the blades 1 and 2, while rivet 5 acts as a journal pin for the respective springs 7 and 8. Springs 7 and 8 are identical in size and function and, therefore, the description of one will apply to both. From Figures 3 and 4 it will be noted that body 3 is provided with covering side plates 9 and 10 which may be bone or other material, and which are formed with cut-

40 out portions 11 and 12 for accommodating the respective springs, 7 and 8 and also accommodating the respective roller bearings 13. There is provided a roller bearing 13 for each of the blades 1 and 2. Arranged interiorly of the

45 side plates 9 and 10 are metallic plates 14 and

15, and these plates are each provided with an arc-shaped slot 16 at each end, the arc being struck from the center of the respective pins 4 and 6. The roller bearings 13 are merely hardened rollers loosely fitted into the apertures 17 in the respective blades 1 and 2 while the journal pins 4 and 6 loosely extend through suitable apertures 4' in the respective shanks 22.

As shown in Figure 4, the roller bearings 13 extend through the blade 1, side plates 14 and 15 and into the cut-away portions 11 and 12 of side plates 9 and 10. The respective springs 7 and 8 are provided at each end with an arc-shaped bearing surface 18 adapted to continually rest against the respective roller bearings 13 so as to resiliently and yieldingly hold the blades either in an open position or closed position. As shown in Figure 1, the roller bearing 13 of blade 1 engages the inner portion of the bearing surface 18 while anti-friction pin or roller bearing 13 of blade 2 engages the outer portion of the opposite bearing surface 18. In addition to having the members just described, there is provided a back 19 which acts to space the plates 14 and 15 and also presents at each end a shoulder 20 against which the squared portions 21 of the respective shanks 22 rest when the blades are open.

From Figure 3 it will be noted that the pin 5 extends through the back 19, though the respective journal pins 4 and 6 do not. It will thus be seen that the back does not act as a spring, but merely as a stop at each end, while the springs 7 and 8 are arranged interiorly of the metallic plates 14 and 15. The openings or cut-away portions 11 and 12 extend from near one end to near the opposite end of the side plates 9 and 10 so as to cover the respective springs and other parts while allowing these parts to freely function. In opening and closing the blades, the springs function to resist both the opening or the closing until the blades pass a right angle position in respect to the body. In this way the springs function to positively keep the blades either opened or closed.

What I claim is:

1. A pocket knife, comprising a body

formed with a pair of spaced plates, a covering plate for each of the spaced plates, a back arranged between the first mentioned plates, a blade pivotally connected with said plates, a 5 pair of springs extending longitudinally of said plates and loosely embedded in said cover plates, and a roller bearing carried by the shank of said blade and extending through said spaced plates and over the respective 10 ends of said springs for engaging one end of each of the respective springs, said springs acting to hold the blade open or closed, said roller bearings rolling over the end portions of said springs as the blade is moved from 15 one position to another.

2. In a pocket knife, a body provided with a rivet acting as a pivot pin, a blade pivotally mounted on said pivot pin, a roller bearing loosely mounted in the shank of said blade 20 on the opposite side to the cutting portion of the blade, a pair of side plates forming part of said body and constructed with arc-shaped slots for permitting said roller bearing to move in a half circle, and a pair 25 of flat springs pivotally mounted near the middle of said body positioned so that their ends will rest continually against the end portions of said roller bearing for urging the roller bearing so that said blade will remain open or closed.

3. In a pocket knife, a blade formed with a shank, said shank having an aperture near the center and a second aperture near the end and a body structure including a pair of metallic plates, each plate being formed with an arc-shaped slot and an aperture, a journal pin extending through the apertures in said plates and the center aperture of said shank, a roller bearing extending loosely 40 through the second aperture in said shank and through the slots in said plates, a pair of spaced parallel spring members pivotally mounted near the center of the body and extending to a position to overlap said slots, 45 one end of each of said springs being arc-shaped so as to present bearing surfaces, said bearing surfaces acting on said roller bearings to resiliently hold the blade in an open position or a closed position.

4. A pocket knife, comprising a pair of metallic plates, each plate having an aperture near each end and an arc-shaped slot partially surrounding the respective apertures, a covering side plate for each of the 50 first mentioned plates, each of said covering side plates being formed with a cut-away portion, a spring arranged in each of said cut-away portions extending from near one end to near the opposite end of said first mentioned plates, said springs being pivotally connected to said first mentioned plates at the center thereof, a pivotal pin extending through each of said apertures, a blade mounted on each of said pivotal pins, and 55 an anti-friction pin extending from the shank

of each of said blades through the respective slots in said plates, said springs being positioned so that their ends will engage said last mentioned pins for resiliently holding the same in either end of the respective slots so 70 as to hold the blades in an open or closed position.

Signed at Ellenville, in the county of Ulster and State of New York, this 3rd day of October A. D., 1927.

WILLIAM CARMAN.
